United States Patent Office

Des. 222,735
Patented Dec. 14, 1971

222,735

BOWL

Karl Wiedemann, 519 Fireside Lane,
Cherry Hill, N.J. 08034

Filed May 25, 1970, Ser. No. 23,180

Term of patent 14 years

Int. Cl. D7—01

U.S. Cl. D44—15

FIG. 1

FIG. 2

FIG. 3

FIG. 4

FIG. 1 is a front elevational view of the bowl showing my new design;
FIG. 2 is a rear elevational view;
FIG. 3 is a side elevational view; and
FIG. 4 is an enlarged scale sectional view on line 4—4 of FIG. 1.

I claim:

The ornamental design for a bowl, substantially as shown.
